UNITED STATES PATENT OFFICE.

SAMUEL A. SNELL, OF ST. LOUIS, MISSOURI, ASSIGNOR TO HARRY W. BUNDY, OF DETROIT, MICHIGAN.

STEERING-WHEEL RIM AND METHOD OF MAKING THE SAME.

Application filed September 22, 1922. Serial No. 589,876.

To all whom it may concern:

Be it known that I, SAMUEL A. SNELL, a subject of the King of Great Britain, residing at St. Louis, State of Missouri, have invented a certain new and useful Improvement in Steering-Wheel Rims and Methods of Making the Same, of which the following is a full, clear, and exact description, such as will enable others skilled in the art to which it appertains to make and use the same, reference being had to the accompanying drawings, forming part of this application.

My invention relates to tubular constructions such as are adapted for use for steering wheels of motor cars and the like, and consists in an improved method and product whereby a corrugated rim is made economically from a metal tube stock.

20 The objects of my invention are to produce a rim of metal tubing having the corrugations now usually provided on wood or composition rims of much greater cost. I also desire to provide an improved assembly of tubular metal rims with the wheel spokes.

In the accompanying drawings which illustrate a selected embodiment of my invention and the means for producing same,—

30 Figure 1 is a fragmentary view of a wheel rim showing the connection thereto of one of the wheel spokes.

Figure 2 is a cross section of the stock from which the rim is formed.

35 Figures 3, 4 and 5 are sections on lines 3—3, 4—4, and 5—5 of Figure 1.

Figures 6 and 7 are sections through those portions of the dies which form the rim sections shown in Figures 4 and 5, respectively.

40 A suitable length of the tubing 1 shown in Figure 2 is bent to form a ring in any practical manner and the ring thus formed is placed between two annular dies 2 and 3 which combine to form a ring of a general oval contour in cross section, the cross sectional circumference of which is a little less than the circumference of the circular tube 1. At intervals about the external periphery of this die rim, recesses 4 are provided by drilling through the die, and on the interior periphery of the die ring, at intervals located on different radii from the radii of openings 4, recesses 5 are provided by forming elongated holes 5, equal in length to the short diameter of the die ring. In other 55 words, the upper and lower sides of the

openings 5 are tangent with the upper and lower surfaces of the ring. The width of holes 5 approximate the diameter of holes 4.

Upon the compression of the circular stock between these dies, all of the metal of the stock is distorted because of the difference in cross sectional circumference of the stock and the normal oval of the dies, as well as because of the difference in their contours, the surplus metal in the portions intermediate openings 4 and 5 flowing or being extruded into these openings so as to form bosses 6 and 7, respectively, upon the external and internal periphery of the rim. The cross sectional circumference of the rim taken over these bosses will be slightly greater than the circumference of the tubular stock.

Bosses 6 will resemble a series of small circular knobs about the exterior periphery of the rim, and bosses 7 will resemble a series of crescent extrusions having their greatest projection on the inner periphery of the rim from where they converge toward the normal rim surface and merge with the upper and lower faces of the latter.

The rim thus formed is uniform in thickness and is smooth except at the bosses which form a series of corrugations nicely accommodating the grip of a human hand.

45 I am aware of the upsetting of straight tubes by means of gripping dies forced together lengthwise of the tube to form extruded bosses for various purposes, but such a method is impractical for the efficient production of articles in quantities and the resulting product would not be a commercial article as the continuous corrugation around the cross sectional circumference of the rim would be objectionable.

50 In the preferred assembly of my rim with the wheel spokes 8, I provide arcuate flanges on the ends of the latter adapted to fit the oval contour of the rim. As the rim is of insufficient thickness to afford adequate metal for attaching screws, I reinforce the rim at these points by the insertion of short bushings 9 into the stock before the latter is bent to its ring shape. These bushings are located at predetermined points in the tube 55 before it is bent so that in the finished rim each will occupy a position intermediate two bosses 7, the corresponding boss at that point being eliminated. These bushings 9 are then bent and shaped with the tubular stock.

Obviously variations in the location and contour of the bosses and other modifications of my invention may be made without departing from the spirit thereof as expressed 5 in the appended claims.

I claim:

1. A steering wheel rim formed of circular tubing stock compressed to form sectors of bossed cross sectional area of larger circumference than said stock and intermediate 10 sectors of oval cross sectional area of less circumference than said stock.

2. The method of making a corrugated steering wheel rim which comprises the die 15 forming of external bosses on a metal tube.

3. The method of making a corrugated steering wheel rim which consists in the compression of a metal tube between dies having a smaller cross sectional area than 20 said tube throughout a portion of their extent and having a larger cross sectional area

than said tube throughout intermediate portions of their extent.

4. The method of making a corrugated steering wheel rim which consists in the 25 compression of a metal tube between two annular dies having a general cross section of different outline and smaller section than the tube so as to distort all of the metal of the latter and having recesses at intervals 30 to receive extruded portions of the tube to form bosses on the periphery of the latter.

5. A steering wheel rim formed of tube stock compressed at intervals to form portions each having a bossed cross section of 35 larger circumference than said stock and to form intermediate portions having a cross section of less circumference than said stock.

In testimony whereof I hereunto affix my signature this 19th day of September, 1922. 40

SAMUEL A. SNELL.
